UNITED STATES PATENT OFFICE.

JACOB RANZ, OF ST. LOUIS, MISSOURI.

HAIR CURLER.

Application filed May 23, 1922. Serial No. 562,997.

To all whom it may concern:

Be it known that I, JACOB RANZ, a citizen of the United States, residing at city of St. Louis and State of Missouri, have invented a certain new and useful Improvement in Hair Curlers, of which the following is a full, clear, and exact description, such as will enable others skilled in the art to which it appertains to make and use the same, reference being had to the accompanying drawings, forming part of this application, in which—

Figure 1 is a detail view of my improved hair curler.

Figure 2 is an enlarged vertical sectional view through the front end thereof.

Figure 3 is a top plan view of the front end.

Figure 4 is a horizontal sectional view through the rear end.

Figure 5 is a rear end elevational view, and

Figure 6 is a side elevational view.

This invention relates to a new and useful improvement in hair curlers, the objects being to construct a device of the character described which is simple, cheap to manufacture, and efficient in service. My improved hair curler may be used "cold" or in connection with a heating element. The article consists primarily of a hollow tube adapted to receive a plug in one end, which plug may or may not be heated, the opposite end of said tube being crimped to press upon the terminal ends of a refolded spring wire loop which normally occupies a position away from the tube whereby the hair may be wound around the tube, after which the closed end of the wire loop is stressed or bent over the forward end of the tube and held in its closed position by means of the plug, while clamping the hair around the tube. The closed end of the loop is provided with shoulders so as to prevent the hair wound upon the tube from coming in contact with the plug, if the same is heated, said shoulders also serving to free the front end of the tube from strands of hair which might extend over the tube opening thereby preventing the introduction of the plug into the tube or possibly the breaking of the hair when the tube is inserted through the opening.

In the drawings, 1 indicates a tube preferably cylindrical and having its ends slightly round, as shown. Originally, this tube is a

straight cylinder open at both ends. 2 is a spring wire loop whose ends are bent towards each other as shown in Figure 4. These bent ends are inserted into one end of the tube, which I designate the rear end, 60 after which, by a suitable press the tube is crimped or flattened, as shown in Figure 5. The shoulder 1^a formed by this flattening process extends in front of the bent ends 2^a, as shown in Figure 4. This prevents the ends of the loop from moving inwardly with respect to the tube and the flattened compressed portions 1^b extending between the reaches of the loop extremities prevent the ends of the loop from being withdrawn from 70 the tube. The bent ends 2^a prevent rotation of the loop ends in the crimped end of the tube.

As shown in Figures 1 and 6, the loop is bent forwardly and upwardly, its front end being connected by means of a cross wire 2^b whose extremities are connected by reaches 2^c to portions 2^b, the latter forming shoulders. 3 indicates a plug preferably formed of hollow metal having a wooden or insulation handle 3^a at its forward end, the inner end of said handle being provided with an annulus 3^b. This metal plug 3 may be solid, if desired, and may be heated either by the application of external heat or it may contain an electrical heating unit in circuit with the wires 4; or said plug may be used cold.

In operation, the plug is removed, as shown in Figure 1, so as to permit the loop 2 to spring outwardly from the tube thereby enabling the operator to wind the hair upon the tube 1. After the hair is wound upon the tube 1, the forward end of the loop 2 is brought down and moved past the front end of the tube in which movement the end 95 2^b and the reaches 2^c wipe the hair from the end of the tube and from over the opening in the front end of the tube, thereby exposing said opening so that the plug 3 can be readily inserted therein. The plug being 100 inserted in position stresses the loop and locks it in its closed position, and the cross wire 2^b can be seated in the annulus 3^b whereby the plug is prevented from accidental longitudinal displacement. The 105 shoulders 2^a prevent the hair on the tube from sliding off of the tube and coming in contact with the plug.

I claim:

1. A hair curler comprising a tube, and a 110

spring wire loop whose ends are secured and held in position against displacement in one end of said tube.

2. A hair curler comprising a tube, a loop having bent ends inserted within and engaged by the walls of said tube.

3. A hair curler comprising a tube, one end of which is flattened, and a loop whose end portions are held in position by the flattened end of the tube.

4. A hair curler comprising a tube, a loop secured in position in one end of said tube, said tube having flattened portions for engaging said loop, and a removable plug 10 adapted to cooperate with the opposite end of the loop.

5. A hair curler comprising a tube, a loop fixedly mounted in one end of the tube, and normally extending away from the opposite 20 end of the tube, and a removable plug for stressing and holding said loop in closed position.

6. A hair curler comprising a tube, a loop

fixedly secured in one end to said tube, a removable plug insertable in the opposite end 25 of said tube, and means for holding said plug in position against longitudinal displacement.

7. A hair curler comprising a tube, a spring wire loop fixedly secured in one end 30 of said tube, a plug insertable within the tube for holding said loop in its closed position, and means on said plug cooperating with said loop for preventing accidental longitudinal displacement of said plug. 35

8. A hair curler comprising a tube, a loop secured in one end of said tube, said loop having shoulders formed on its opposite or free end and which shoulders cooperate with the tube to prevent displacement of the hair 40 around the tube when said loop is in operative position, and means for holding said loop in operative position.

In testimony whereof I hereunto affix my signature this 18th day of May, 1922.

JACOB RANZ.
